No. 701,052.

Patented May 27, 1902.

M. F. KELLEY.
LASTING MACHINE.

(Application filed July 18, 1901.)

(No Model.)

UNITED STATES PATENT OFFICE.

MICHAEL F. KELLEY, OF MILFORD, MASSACHUSETTS.

LASTING-MACHINE.

SPECIFICATION forming part of Letters Patent No. 701,052, dated May 27, 1902.

Application filed July 18, 1901. Serial No. 68,769. (No model.)

To all whom it may concern.

Be it known that I, MICHAEL F. KELLEY, of Milford, in the county of Worcester and State of Massachusetts, have invented certain new 5 and useful Improvements in Lasting-Machines, of which the following is a specification.

This invention has relation to lasting-machines, and more particularly to that class of 10 machines wherein the upper is secured to the insole by suitable fasteners. In such machines considerable difficulty is experienced in lasting the heel portion of the shoe, owing to the fact that the usual pincers are thrown 15 out of operation at such times or are not used, and consequently the upper is not laid tightly over and caused to conform to the counter, so as to form a perfect heel-seat.

The object of this invention, therefore, is 20 to provide a mechanism applicable for use in such machines for hammering the upper around the back of the heel portion of the shoe to cause it to lie perfectly flat against the counters and last, so that when the upper is secured to the insole it will be stretched 25 tightly and be free from "bunchy" spots or slack places.

Referring to the drawings, Figure 1 represents in side elevation a portion of a lasting- 30 machine equipped with my improvements. Fig. 2 represents a front elevation of the same. Fig. 3 represents the rest for the shoe removed from the machine. Fig. 4 represents a reversed view of the same. Figs. 5 and 6 35 represent sections through the rest and illustrate the device in different positions. Fig. 7 represents a section on line 7 7 of Fig. 5. Fig. 8 represents a section on line 8 8 of Fig. 3. Fig. 9 shows the rest in inoperative position.

The machine shown is a part of the tack-lasting machine commonly in use, and my improvements are shown as applied thereto.

On the drawings, 10 indicates a horizontal 40 sliding head or frame, upon which is supported the tack-driver 11. The holder for the tacks is likewise mounted on said frame, so as to be movable therewith in the usual way. The rest or abutment for the heel portion of 45 the shoe is indicated at 13. It is connected by mechanism, which shall be explained, to a support 14, the latter being attached by

suitable fastening devices to the angular arm 15, depending from the casting 16, the latter being stationary at all times. The support 55 14 is provided with forwardly-projecting ears or lugs 17 17, in which is journaled the tubular end portion 18 of the rest 13. The said tubular end portion is provided with a flat face 19, against which two spring-pressed 60 pins 20 20 are adapted to press to hold the said rest in operative position, as indicated in Fig. 1, but which will permit the said rest to be swung down to inoperative position, as shown in Fig. 9. Said tubular end portion 65 is provided, further, with two stops 21 21, which are adapted to engage the end of the support 14 and limit the forward and upward movement of the rest or abutment 13. The front face of the rest is concave, as at 22, being laterally extended, as shown, so as to afford a relatively large area against which the shoe may be pressed or held.

The hammer which I employ for laying the upper tightly against the last and the counter is indicated as a whole at 23. It is placed 75 in a groove in the said rest, and its operative end lies normally within the face 22 of the rest, as indicated in Fig. 7. The said end of the hammer is laterally enlarged and is adapted to be drawn into the socket 24 in the face 22 by a spring 25, having one end connected to a screw 26, attached to the hammer, and having its other end fastened to a screw-pin 27, secured to the rest or abutment. The 85 screw 26 passes through a slot in the bottom of said abutment, as indicated in Fig. 9. The said hammer is adapted to reciprocate longitudinally of the last and to this end is provided with an adjustable projection 28, having 90 an inclined face 29 at its inner end. This projection is in line with a stop 30, secured to the under side of the tack-holder 12, so that when the said tack-holder is reciprocated the projection 30 will engage the projection 95 28 and carry the hammer forward with it, so as to cause it to extend beyond the face of the rest. Consequently each time the driver 11 is actuated and the tack-box is moved forward with the sliding frame 10 the hammer 100 will be caused to engage the upper and to lay it smoothly against the counter and hold it there while the tack is being driven home. The engaging end of the projection 30 is in-

clined, so that when it strikes against the face 29 of the projection 28 the hammer is slightly raised, so that it has in addition to a longitudinal movement a lateral or upward movement to produce a wiping effect on the upper.

In order to limit the upward movement of the hammer, which may vary according to the inclination of the front of the rest, as will be explained, the said rest is provided with a forwardly-projecting finger 31, whose end is adapted to engage a shoulder 32 on the top of the hammer, as shown in Figs. 5 and 6. The tubular end of the rest is grooved, as shown in Fig. 3 at 33, to provide for the movement of the projection 30. I may term the said projection 30 an "actuator," since it operates or actuates the hammer at each reciprocation of the frame 10. The rest is formed in two parts jointed together on a horizontal axis, being provided with overlapping lugs connected by screw-pins 36 36, said lugs being indicated at 37 and 38, respectively, and the hammer is likewise formed in two parts connected together by a pintle 39. (See Figs. 5, 7, and 8.) Consequently the face of the rest may be held substantially vertically or at an inclination, as shown in Fig. 6, so that the position of the shoe may be varied according to different requirements. The axes of the pivot-pins 36 and the pintle 39 are in alinement when the hammer is withdrawn; but as the oscillatory movement of the loose ends of the hammer and rest is somewhat small and the longitudinal movement of the hammer itself is not very great relatively to the rest there is no danger of the rest and the hammer binding or being prevented from movement about their respective pivots. On the lower end of the rest is formed a hook 40, with which the finger of the operative may be engaged to hold the shoe tightly against the rest or abutment. The rest, which performs the functions of a gage, is adjustable longitudinally, as ordinarily.

The stop 31 may be made thin enough to have a spring action, so as to yield when the hammer engages it and to return the said hammer when the pressure thereon is removed.

Having thus explained the nature of the invention and described a way of constructing and using the same, although without attempting to set forth all of the forms in which it may be made or all of the modes of its use, I declare that what I claim is—

1. A machine of the character described having a hammer for engaging the upper and laying it against the counter during the operation of securing the upper to the insole, and

an abutment against which the end of the shoe may be pressed during the operation of the hammer.

2. A machine of the character described, comprising fastening mechanism, a hammer 65 having a non-yielding flattened end, and means for giving said hammer a wiping stroke against the upper to cause the upper to lie snugly against the counter.

3. A machine of the character described, 70 comprising fastening mechanism, a hammer, having a non-yielding flattened face to engage the upper at the heel end of the shoe, and means for automatically reciprocating said hammer. 75

4. A machine of the character described, comprising fastening mechanism, an abutment for the heel end of the last to rest against, and a hammer in said abutment.

5. A machine of the character described, 80 comprising fastening mechanism, an abutment having a socketed face for the heel end of the last to rest against, and a hammer having a head located in the socket when in its inoperative position. 85

6. A machine of the character described, comprising fastening mechanism, an abutment for the heel end of the last, a hammer reciprocatory in a plane substantially at right angles to the said heel end of the last, and 90 means for actuating said hammer.

7. A machine of the character described, comprising fastening mechanism, a hammer having a non-yielding flattened end and reciprocating in a plane substantially at right 95 angles to the heel end of the last, and means for actuating said hammer to cause its end to move laterally toward the sole of the last to lay the upper flat against the counter.

8. A machine of the character described, 10 comprising fastening mechanism, a hammer reciprocatory in a plane substantially at right angles to the heel end of the last, means for actuating said hammer, and provisions whereby said hammer may be swung bodily to an operative position. 105

9. A machine of the character described, comprising fastening mechanism, a hammer reciprocatory in a plane substantially at right angles to the heel end of the last, means for 110 actuating said hammer, and provisions whereby the head of said hammer may be moved at an inclination to said plane.

In testimony whereof I have affixed my signature in presence of two witnesses.

MICHAEL F. KELLEY.
